UNITED STATES PATENT OFFICE.

ROLAND L. ANDREAU, OF WILMINGTON, DELAWARE, ASSIGNOR TO E. I. DU PONT DE NEMOURS AND COMPANY, OF WILMINGTON, DELAWARE, A CORPORATION OF DELAWARE.

PROCESS OF OXIDIZING ISO-BORNEOL TO CAMPHOR.

1,347,071.

Specification of Letters Patent.

Patented July 20, 1920.

No Drawing.

Application filed November 12, 1917. Serial No. 201,676.

To all whom it may concern:

Be it known that I, ROLAND L. ANDREAU, of Wilmington, in the county of New Castle, and in the State of Delaware, have invented 5 a certain new and useful Improvement in Processes of Oxidizing Iso-Borneol to Camphor, and do hereby declare that the following is a full, clear, and exact description thereof.

10 My invention relates particularly to a process designed for transforming iso-borneol into camphor by the oxidation thereof.

The object of my invention is to provide 15 a process of the above character in which iso-borneol is rapidly and readily transformed into camphor without depending upon the presence of a starter or catalytic agent, such as copper, sodium nitrite, starch, 20 etc. Furthermore in my process mixed nitric and sulfuric acids are used and a nitric acid of a low strength is used.

A further object is to provide a process 25 of this character which is cheaper and more practical than previous processes of a similar nature.

A further object is to provide a process 30 of this character in which the reaction starts spontaneously at the ordinary or a relatively low temperature,—that is to say, below 40° C.,—and which proceeds smoothly and regularly until practically all of the nitric acid has been used up and only a trace thereof 35 remains in the residual weak sulfuric acid with which it is mixed in carrying out the process, and in which the sulfuric acid may be readily recovered for concentration and fortification for further use.

A further object is to use mixed acids 40 containing such a percentage of water as not to have the reaction proceed too violently.

While my invention is capable of being carried out in many different ways, for the purpose of illustration, I shall describe only 45 one way of accomplishing the same herein-after.

For example, I may proceed as follows:

A quantity of mixed nitric and sulfuric acids is made, containing the following pro- 50 portions: 339 kilograms of sulfuric acid, 66°

Bé., and 253 kilograms of nitric acid, 26° Bé., specific gravity 1.22. The mixed acid is introduced into a container, which may be provided with any desired type of stirring device. Thereupon about 1 kilogram of iso-borneol is added to the mixed acid. Only a small amount of the iso-borneol is added in order to avoid having the reaction proceed too violently. If the reaction proceeds too violently the undesirable products, such as resinous compounds and camphoric acid will be formed, and the compounds will become subjected to such violent ebullition that they cannot be retained in the vessel. When the temperature has risen to above 40° C. indicating that the reaction has begun, which will usually be after about 15 minutes, additional iso-borneol is added gradually, and with caution taking care that the temperature of the mass remains between 35° C. 70 and 40° C. during the reaction, continuing the addition until the entire amount of iso-borneol added equals 154 kilograms. The supernatant liquid, which contains the camphor in the form of a loose addition compound with N_2O_5 , is then decanted and run into water, where the camphor precipitates as a solid, and is then washed, centrifuged, dried and purified. In this way a substantially theoretical yield is obtained.

80 While I have described my invention above in detail, I wish it to be understood that many changes may be made therein without departing from the spirit of my invention.

I claim:—

1. The process which comprises oxidizing iso-borneol into camphor by the application of mixed nitric and sulfuric acids.
2. The process which comprises oxidizing iso-borneol into camphor by the application of mixed nitric and sulfuric acids in such proportions as to start the reaction spontaneously.
3. The process which comprises oxidizing iso-borneol into camphor by the application of mixed nitric and sulfuric acids in the proportion of substantially 57% sulfuric acid 66° Bé. and 43% nitric acid 26° Bé.
4. The process which comprises oxidizing

- iso-borneol into camphor by the application of mixed nitric and sulfuric acids, the temperature during at least the first part of the reaction being maintained at 40° C. or less.

5. The process which comprises oxidizing iso-borneol into camphor by the application of mixed nitric and sulfuric acids in such proportions as to start the reaction spontaneously, the temperature during at least the first part of the reaction being maintained at about 40° C. or less.

6. The process which comprises oxidizing iso-borneol into camphor by the application of mixed nitric and sulfuric acids in the proportion of substantially 57% sulfuric acid 66° Bé. and 43% nitric acid 26° Bé., the temperature during at least the first part of the reaction being maintained at about 40° C. or less.

7. The process which comprises oxidizing iso-borneol into camphor by the application of mixed nitric and sulfuric acids, the temperature during at least the first part of the reaction being maintained at approximately 35° C.

8. The process which comprises oxidizing iso-borneol into camphor by the application of mixed nitric and sulfuric acids in such proportions as to start the reaction spontaneously, the temperature during at least the first part of the reaction being maintained at approximately 35° C.

9. The process which comprises oxidizing iso-borneol into camphor by the application of mixed nitric and sulfuric acids in the proportion of substantially 57% sulfuric acid 66° Bé. and 43% nitric acid 26° Bé., the temperature during at least the first part of the reaction being maintained at approximately 35° C.

10. The process which comprises oxidizing iso-borneol into camphor by the application of mixed nitric and sulfuric acids, the iso-borneol being added to the mixed acid initially in a small quantity until the reaction is started, and thereafter adding further quantities gradually.

11. The process which comprises oxidizing iso-borneol into camphor by the application of mixed nitric and sulfuric acids in such proportions as to start the reaction spontaneously, the iso-borneol being added to the mixed acid initially in a small quantity until the reaction is started, and thereafter adding further quantities gradually.

12. The process which comprises oxidizing iso-borneol into camphor by the application of mixed nitric and sulfuric acids in the proportion of substantially 57% sulfuric acid 66° Bé. and 43% nitric acid 26° Bé., the iso-borneol being added to the mixed acid initially in a small quantity until the reaction is started, and thereafter adding further quantities gradually.

13. The process which comprises oxidizing iso-borneol into camphor by the application of mixed nitric and sulfuric acids, the temperature at least during the first part of the reaction being maintained at 40° C. or less, the iso-borneol being added to the mixed acid initially in a small quantity until the reaction is started, and thereafter adding further quantities gradually.

14. The process which comprises oxidizing iso-borneol into camphor by the application of mixed nitric and sulfuric acids in such proportions as to start the reaction spontaneously, the temperature at least during the first part of the reaction being maintained at 40° C. or less, the iso-borneol being added to the mixed acid initially in a small quantity until the reaction is started, and thereafter adding further quantities gradually.

15. The process which comprises oxidizing iso-borneol into camphor by the application of mixed nitric and sulfuric acids in the proportion of substantially 57% sulfuric acid 66° Bé. and 43% nitric acid 26° Bé., the temperature at least during the first part of the reaction being maintained at 40° C. or less, the iso-borneol being added to the mixed acid initially in a small quantity until the reaction is started, and thereafter adding further quantities gradually.

16. The process which comprises oxidizing iso-borneol into camphor by the application of mixed nitric and sulfuric acids, the temperature during at least the first part of the reaction being maintained at approximately 35° C., the iso-borneol being added to the mixed acid initially in a small quantity until the reaction is started, and thereafter adding further quantities gradually.

17. The process which comprises oxidizing iso-borneol into camphor by the application of mixed nitric and sulfuric acids in such proportions as to start the reaction spontaneously, the temperature during at least the first part of the reaction being maintained at approximately 35° C., the iso-borneol being added to the mixed acid initially in a small quantity until the reaction is started, and thereafter adding further quantities gradually.

18. The process which comprises oxidizing iso-borneol into camphor by the application of mixed nitric and sulfuric acids in the proportion of substantially 57% sulfuric acid 66° Bé. and 43% nitric acid 26° Bé., the temperature during at least the first part of the reaction being maintained at approximately 35° C., the iso-borneol being added to the mixed acid initially in a small quantity until the reaction is started, and thereafter adding further quantities gradually.

19. The process of oxidizing iso-borneol

into camphor in such a manner as to avoid the production of resinous compounds which comprises inducing a reaction between mixed nitric and sulfuric acids and iso-borneol under controlled temperature conditions.

20. The process of oxidizing iso-borneol into camphor which comprises bringing together iso-borneol and mixed nitric and sul-

furic acids at such a rate as to avoid violent ebullition.

In testimony that I claim the foregoing I have hereunto set my hand.
